CLAIM

The ornamental design for a memory card adapter, as shown and described.

DESCRIPTION

FIG. 1 is a perspective view of a first embodiment of a memory card adapter showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

Portions in broken lines are for illustrative purposes only and form no part of claimed design. Dot-dash broken lines define boundaries of, but are not included in, the claimed design.
